FIG. 4.

FIG. 5.

INVENTOR
Clifford M. Watrous,

BY
Jeff Rubin
ATTORNEY

UNITED STATES PATENT OFFICE.

CLIFFORD M. WATROUS, OF EAST HAMPTON, CONNECTICUT, ASSIGNOR TO GONG BELL MANUFACTURING COMPANY, OF EAST HAMPTON, CONNECTICUT, A CORPORATION OF CONNECTICUT.

TOY TELEPHONE.

Application filed June 8, 1922. Serial No. 566,903.

To all whom it may concern:

Be it known that I, CLIFFORD M. WATROUS, a citizen of the United States, and a resident of East Hampton, in the county of Middlesex and State of Connecticut, have invented certain new and useful Improvements in Toy Telephones, of which the following is a full, clear, and exact description, whereby anyone skilled in the art may make and use

10 the same.

The invention relates to toys and is particularly directed to toy telephones of the general type disclosed in my co-pending application, Serial No. 1,476,641 filed June 15 11th, 1921, which has become Patent No. 1,419,902, dated June 13, 1922.

The main object of the invention is to provide a telephone of the "desk set" type in simulation of the standard telephone set 20 arranged to give a ringing signal upon movement of the receiver hook and arm or lever. The device, as a whole, is practically a miniature replica of the ordinary standard receiver and transmitter telephone set.

25 It involves as elements, a base, standard, a transmitter surmounting the standard, a receiver with cord attachment (simulating the wire connections) and a receiver hook or lever which mechanically actuates a signalling device.

30 In my co-pending application there is illustrated a gong with its base, secured to the standard, said gong being actuated by a movement of the receiver hook and lever.

35 The present invention is arranged for striking a double gong which will give a chime effect. This chime effect is quite pleasant to the ear and avoids the harsh ringing of the single gong such as described

40 in my co-pending application.

Naturally, children in playing with one of these toys are prone to ring the signalling device as much as possible. With a single gong this becomes annoying and I have, 45 therefore, endeavored to overcome this disturbing condition by utilizing a pair of gongs of different tones which give a clear signal but with a soft chime effect.

50 Referring to the drawings:

Figure 1, is a view in elevation illustrating the device.

Figure 2, is a side elevation looking at the

Figure 3, is a detailed view of the interior of one of the gongs, the striker and connected gear.

Figure 4, is a detailed view of the receiver hook and lever for actuating the striker.

Figure 5, is a detailed sectional view through the transmitter illustrating the manner of securing the parts.

Toy telephones of one sort or another have been employed heretofore, but so far as applicant knows, there has not been produced a toy, simulating in every respect the standard desk type of 'phone. This type of 'phone may be readily carried about in the hands of the child, and provides educational features as well as a source of amusement.

In the accompanying drawings, numeral 70 1, denotes the base to which is secured the standard 2. The standard 2, is surmounted by a cap 3, which has a projecting lug 4, providing a pivotal connection 5, for the transmitter 6, and mouthpiece 7. The 75 transmitter 6, is cupped up from sheet metal and has an overlying cover 8, centrally perforated to receive a pivoted lever 9, which lever is so formed as to secure the transmitter element 6, cover plate 8, and mouthpiece 7.

The pivoted lever 9, is stamped up from the strip of metal, perforated as at 11, to engage a pivotal connection 5. It has a shoulder 12, against which the base of the transmitter 6, rests and also has a shoulder 13, against which the base of the mouthpiece 7, rests. The outer end of the member 9, is scarfed at opposite sides as at 14, and after the parts are assembled, lugs 15, are pressed 80 down from the scarfed end 14, to provide a permanent holding of the various elements.

85 The receiver hook 16, at the end of the lever 17, which supports the receiver 18, and serves to actuate the gong striking mechanism.

90 The gong striking mechanism consists of a casing 19, having a central shaft 20, extending therethrough and upon which shaft are mounted gongs 21, 21'. The lever 17, is pivoted as at 22, to the casing 19. The said lever terminates in a rack bar 23, which meshes with a pinion 24. The pinion 24, is secured to a shaft 25, which 95 extends through the casing 19, and bears at 100 its outer ends, on opposite sides of the casing

105

19, gears 24', 25'. These gears, in turn, mesh with pinions 26, 27, loosely mounted on the shaft 20, although secured to a rotary striker frame 28. There is a striker frame 5 for each gong and these strikers, thru their pellets 29, engaging lugs 30, of the respective gongs, give when rotated, a rapid vibration of the gongs.

As there is an independent rotary striker 10 for each gong and the gongs are of different tones, it is quite apparent that there is a chime effect of unusual brilliancy and "blend" of tone.

The casing 19, has an extended bracket 15 31, of suitable form to be clamped to the standard 2, as by screws 32. It is, therefore, possible to adjust the gong mechanism on the standard 2, in any desired position.

The pivoted receiver lever and its hook is 20 normally held at one limit of its play by a spring and it follows that a downward movement of the hook and receiver 18, rotates the pinion 24, gears 24', 25', and striker pinions 26, 27. As soon as pressure is released on the receiver and its hook 16, there 25 will be a rotation of the strikers in opposite direction. The effect of this is to give a distinct sounding of the gongs on both movements of the receiver hook and lever.

It will be seen that the casing 19 lies 30 centrally between the gongs 21, 21', and that the lever 17, whose rack bar end 23 extends within the casing 19, has its end 16 that is shaped to constitute a hook for the receiver 18 extended laterally, thus permitting the receiver to be supported behind the signalling mechanism and between it and the standard 2, as represented in Fig. 2, and also to be brought relatively close to the standard 40 when viewed from the front as shown in Fig. 1. This arrangement makes a very compact article, no portion of which extends much outside of the circle defined by the base 1, with the advantages of increased attractiveness in appearance and material reduction in the size of the cartons in which the toys are packed for shipment and sale, as compared with an arrangement where the signal-operating and receiver-supporting 45 lever is radial, in its general disposition, to the standard 2.

Practically all of the parts in the mechanism may be formed from stampings of sheet metal. These provide a cheap method 50 of manufacture and make it possible to assemble the uniformly produced parts at a minimum cost.

It is apparent that the exact details of the construction above illustrated may be modified without departing from the spirit or intent of the invention.

What I claim as my invention and desire to secure as Letters Patent is:

1. In a toy telephone, including a base, standard, transmitter and receiver, a pair

of gongs operatively supported upon the standard and separated from each other, a casing arranged between the gongs, a lever having one end exposed and its other end formed into a gear segment and arranged within the casing, striking mechanisms for the respective gongs, and two sets of gearing operatively connected to the striking mechanisms, arranged to be operated by the gear segment of the lever.

2. In a toy telephone, having a base, standard, transmitter and receiver, a casing supported upon the standard, a stationary shaft extending through and projecting beyond the casing, gongs supported on the shaft and located on either side of the casing, a second shaft rotatably supported in the casing, a lever having an end formed into a gear segment, extending within the casing and engaging means to turn the rotatable shaft as the lever is moved, striking means for the gongs supported upon the stationary shaft, and gearing between the rotary shaft and the striking means.

3. In a toy telephone having a base and standard, an imitation transmitter at the upper end of the standard and an imitation receiver, a casing secured to the standard below the transmitter, a lever having an end extending into the casing and an exposed end formed into a hook for the imitation receiver, gongs arranged on either side of the casing and separated therefrom, striking means for the respective gongs, and gear mechanism operatively connected to both striking means operated by the said lever.

4. A toy telephone such as described in claim 3, the exposed end of the lever being bent laterally so the receiver, when supported thereon is located close to the standard and between the gongs and the standard.

5. In a toy telephone, the combination with a base, standard, and imitation transmitter and mouth piece supported by the standard, of means for supporting the transmitter and mouth piece, consisting of a thin metal bar formed with a shoulder against which rests a part of the transmitter, and with a second shoulder in advance of the first-named shoulder against which rests the mouth piece, the bar having also integral lugs adjacent to the second shoulder adapted to secure the mouth piece in place.

6. An imitation transmitter and mouth piece for a toy telephone, consisting of a thin metal bar adapted to serve as a support for the transmitter and mouth piece, the bar having two shoulders spaced apart, and bendable lugs adjacent to the second or outermost shoulder, a cup-shaped part serving as the base of the transmitter, perforated and adapted to rest against the innermost shoulder of the bar, a perforated plate adapted to cover the open end of the cup-shaped base and to be slipped over the bar,

and a cup-shaped mouth piece perforated to fit over the bar and rest against the outer shoulder and against the plate covering the transmitter base, the mouth piece being held 5 in position against its shoulder on the supporting bar and the several parts properly assembled and held by the lugs of the supporting bar.

7. As an article of manufacture for a toy 10 telephone, a transmitter comprising a supporting bar for a mouthpiece having a shoulder, a transmitter part resting against the shoulder, a closure for the transmitter part including a mouthpiece and integral lugs 15 upon the supporting bar within the mouthpiece, said lugs adapted to secure the transmitter parts in place upon the supporting bar.

8. As an article of manufacture of a toy 20 telephone, a transmitter comprising a pivoted support, a transmitter part engaged therewith, a closure for the transmitter part including a mouthpiece and means structur-

ally integral with the support for clamping the transmitter part in place thereon. 25

9. An article of manufacture in a toy telephone, a transmitter comprising a supporting element for a mouthpiece, a stop for localizing the mouthpiece and appurtenant parts upon the support, a transmitter part 30 and a closure for the transmitter part including the mouthpiece and means structurally integral with the supporting element for clamping the transmitter parts and the mouthpiece to the support. 35

10. As an article of manufacture for a toy telephone, a transmitter comprising a supporting bar for a mouthpiece, having a shoulder, a transmitter part resting against the shoulder, a closure for the transmitter part including a mouthpiece and an upset 40 member from the supporting bar within the mouthpiece, said upset member adapted to secure the transmitter parts in place, upon the supporting bar.

CLIFFORD M. WATROUS.
